9 Claims. (Cl. 171—206)

This invention relates to motor or generator construction, and more particularly to the armature construction therefor.

One of the objects of this invention is to provide an armature, particularly for a machine handling direct current, which is simple in construction, practical in form, and which may be economically produced. Another object is to provide a direct current armature in which, for a given size of core, a maximum output rating may be obtained. Another object is to provide an armature of the above mentioned character which is dependable, thoroughly practical, and efficient in operation. Another object of this invention is to provide an armature of the above mentioned character which will have improved commutation characteristics and which, particularly, will achieve a reduction of sparking at the commutator and a reduction of objectionable heating. Other objects will be in part obvious or in part pointed out hereinafter.

The invention accordingly consists in the features of construction, combinations of elements, and arrangements of parts, all as will be illustratively described herein and the scope of the application of which will be indicated in the following claims.

In the accompanying drawing, in which are shown several of the various possible embodiments of my invention,

Figure 1 is a fragmentary cross section through a slotted portion of an armature and includes a diagrammatic representation of the connections to the commutator, and

Figure 2 is a view similar to that of Figure 1 but showing a modified form of my invention, with a different arrangement of conductors in the armature slot.

Similar reference characters refer to similar parts throughout the several views in the drawing.

As conducive to a clearer understanding of certain features of my invention, it may at this point be noted that, in the commercial production of direct current motors and generators, it has been found expedient and desirable to carry a supply of only a minimum number of different sizes of armature core punchings or laminations. It is then necessary to use any one type of punching for machines of several different ratings. With a change of rating, such as a change in voltage of the machine or a change in its rated speed or rated current output, the number of conductors per slot of necessity must differ. One of the dominant aims of this invention is to

provide a simple and thoroughly practical manner of using standard punchings, core sizes, and coils to produce a machine of simple, practical and inexpensive construction, yet one which is highly efficient in operation and one in which commutation troubles are minimized.

As further conducive to a clearer understanding of certain features of my invention, the following may be pointed out:—

The commutator segments in the case of D. C. dynamo armatures are, generally speaking, equal in number to the number of wires or coil sides respectively situated in the extreme peripheral position. In those cases in which neither brush displacement nor reversing poles may be or are to be employed, and in which, therefore, the number of wires in relation to one commutator segment require to be reduced as far as possible, the number of segments have to be increased as compared with the usual embodiment, for example, doubled. In this case, however, it is no longer possible to arrange all coil sides, as is the rule, in two circumferential layers. The coil sides, therefore, have to be arranged in four circumferential layers and in that case, in each slot, four coil sides lie above each other.

The provision of, for example, two-by-two winding elements in a radial direction of the slots necessitates that the number of superimposed wires situated in the one slot be a multiple of the number of the winding elements. Now it may occur that, from an economical standpoint, the most desirable number of wires in a radial slot layer is, for example, six, and in such cases it has hitherto been necessary to employ eight wires in each radial slot layer, i. e. an unnecessarily high number of armature conductors resulting in a considerably increased resistance of the armature, i. e. in diminished capacity of the dynamo, assuming the number of slots could not be sufficiently reduced. Further the increased radial length of the slots, necessary on account of the increased number of wires in one radial layer, involves a substantially less perfect commutation.

The present invention relates to a method of winding and a winding which enables a number of wires in a radial layer, which is not commensurable with or a multiple of four, to also be employed in such cases in which the superimposed wires situated in the radial direction of the slot require to be divided into four coil sides. The invention includes the feature of not making the number of wires distributed over the segments the same in the case of all commutator segments, but alternately greater and less than

that which would conform with the most economical nominal value.

Referring now to the drawing and more particularly to Figure 1, there is shown at T a section of a portion of an armature core with a slotted portion S in which is laid, for example, the four coil sides C, D, L and K of a portion of the armature winding. The coil sides are maintained secure in the slot by the top stick U which interfits with the grooved portions V provided in the upper portions of the slot wall. Each of the bottom coil sides C and D comprises two individual conductors wound parallel. The coil including the lower coil side C may, for example, lay off to the left where it interfits another slot (not shown) in which it becomes the second coil side from the bottom. The coil including the second coil side D may, for example, lay off to the right and be lodged in a third slot (not shown) in which it has its other coil side at the bottom.

The coil sides K and L each comprise, for example as shown, four conductors connected to form two individual groups of two series-connected conductors in each group, lying in the same radial layer of conductors, both groups being wound parallel.

Conductors C¹ and C² of the bottom coil side C are respectively connected by conductors E and F to the respective commutator segments A⁴ and A² of the commutator A. The conductors K¹ and K² of the third coil side K are respectively connected by conductors M and N to the respective commutator segments A³ and A¹. Conductors D¹ and D² of the second coil side D are respectively connected by the leads G and J to the commutator segments B⁴ and B² of the group B which is suitably spaced along the commutator periphery from the segments of group A. The top coil side L has its parallel conductors L¹ and L² respectively connected by means of conductors O and P to the respectively intervening commutator segments B³ and B¹.

It is to be noted that the parallel-wound conductors of each coil side are connected to commutator segments with one segment intervening. It is also to be noted that the intervening segment is connected to a coil side which is spaced in a radial direction from the first mentioned coil side by an intervening coil side, and that, while the coil of the lower coil side C and third coil side K, belonging to a coil laying off to the left, are connected to the section A of the commutator, the intervening or second coil side D and the top coil side L are parts of coils laying off to the right and are connected to the segment B of the commutator. It is to be further noted that it is the coil sides of the smaller number of ampere-turns which are placed in the bottom of the slots. With this construction the coils of lesser number of ampere-turns are so positioned that their respective self-inductances are approximately the same as the self-inductances of the coils having the larger number of ampere-turns which are positioned in the upper portions of the slots, since, for similar coils, the inductances increase with the depth to which they are placed within the slot. Thus I achieve a compensation between the variously sized coils and a consequent improvement in commutation.

The arrows indicated by points (representing arrow heads) and the crosses, representing arrow tails, indicate not the direction of the current but the direction of the single wires of the winding departing from the inner point of connection to the commutator.

In the hand-wound armature construction, in which the various layers of windings are shown in Figure 2, the lower layer C is connected by conductors E and F to the commutator segments A⁴ and A² of the group of segments A and is connected in series with a layer of conductors corresponding with the layer D, but situated in another slot laying off to the left. The next layer of conductors D is connected by end turns G and J to the commutator segments B⁴ and B² of the group of segments B, being connected in series with the conductors of a layer in another slot laying off to the right, corresponding with the layer C. The conductors of the next layer H are connected with the layer W over conductors of another slot laying off to the left, corresponding with the layer I. The conductors of the layer H are spaced from the layer W by the intervening layer I and are connected by end turns Q and R to the commutator segments A³ and A¹ of group A. The aforementioned layer of conductors I is connected with the layer X over conductors in another slot laying off to the right, corresponding to the layer W, by means of the end turns Y and Z is taken to the commutator segments B¹ and B³ of the group of segments B. Thus, with this construction, one layer W of the series-connected groups H and W is sandwiched in between the group of series-connected conductors I and X. Also one layer I of the group of series-connected conductors I—X is sandwiched in between the layers H and W of the group of series-connected conductors H—W. This tends to equalize the inductances of both kinds of coils as will now be clear in view of what has been above set forth in connection with the arrangement of Figure 1. An equalization of the inductances of the coils H—W and I—X (which are of greater number of ampere-turns) and of coils C and D (which have a lesser number of ampere-turns) is effected by locating the coils of lesser turns at the base of the slots. In Figure 2, also, the arrows indicated by points (representing arrow heads) and the crosses (representing arrow tails) do not indicate the direction of the current flow but the direction of the single wires of the winding departing from the inner point of connection to the commutator.

Thus, it will be seen that, due to certain features of my invention, there is provided an armature winding in which, for a number of armature wires lying above each other in a radial direction and which number is not commensurate with or is not a multiple of four, the possibility exists of arranging four coil sides above each other in a radial direction in order to be able to employ an increased number of commutator segments for insuring good commutation. Thereby it is made possible to provide a relatively high number of segments in the commutator without being forced to increase the number of conductors lying above each other in radial direction in the slots.

Thus it will be further seen that, with my invention, there is provided an armature winding in which, for a given size of armature core and slot construction, the slots may be filled with the various conductors to give an efficient and compact construction and yet by virtue of the equalization and distribution of the armature coil inductance, the commutation is improved. It will also be seen that there has been provided in this invention a construction in which the several objects hereinbefore noted together with many other

oughly practical advantages are successfully achieved. It will be seen that the construction is of a thoroughly practical nature, is capable of simple and inexpensive manufacture, and is well adapted to meet the varying conditions of actual use.

As many possible embodiments may be made of the above invention and as many changes might be made in the embodiment above set forth, it is to be understood that all matter hereinbefore set forth or shown in the accompanying drawing is to be interpreted in an illustrative and not in a limiting sense.

I claim:

1. In apparatus of the character described, in combination, a slotted armature core, a commutator having a plurality of segments, a plurality of groups of parallel-wound conductors spaced within any one slot of said armature core, and connections from the conductors of alternate groups to adjacent commutator segments.

2. In a direct current machine including a slotted armature and a commutator, an armature winding comprising a plurality of groups of parallel-wound conductors spaced within the base of said armature slots, and a second plurality of groups of parallel-wound conductors spaced in the upper portions of said armature slots, and means for connecting parallel-wound conductors of said first mentioned group to alternate commutator segments, and means for connecting parallel conductors of one of said second mentioned groups to segments intervening said first mentioned group.

3. In apparatus of the character described, in combination, an armature, a commutator having a plurality of segments, an armature winding comprising single coils with different numbers of windings and which coils are arranged in such a way that in each slot of the armature four coil sides lie above each other in radial direction, and connections for connecting windings of certain of said coils to alternate commutator segments, and means for connecting windings of others of said coils to segments intervening said alternate commutator segments.

4. In apparatus of the character described, in combination a slotted armature, a commutator having a plurality of segments, an armature winding comprising two groups of coils, the one group consisting of coils with a smaller number of conductors than those of the other group, the said coils being arranged in such a way, that in each slot two coil sides with a smaller number of conductors lie on the bottom of the slot and two coil sides with a larger number of conductors lie above

these coil sides, and connections from said coils to the said commutator.

5. In armature construction, in combination, a slotted armature core, a commutator having a plurality of segments, a winding comprising groups of coils, one group consisting of coils with a smaller number of conductors than those of another group, the coils of the said groups being arranged in such a way that in each armature slot there are contained a plurality of coil sides, at least one of which is of a coil of said one group and at least another of which is of a coil of said other group, connections from the conductors of the coils of one group to alternate commutator segments, and connections from the conductors of the coils of another group to intervening commutator segments.

6. An armature construction as claimed in claim 5 in which the coil side at the bottom of the slot is of a coil of the group having a smaller number of conductors.

7. An armature construction as claimed in claim 5, in which there are at least four coil sides in each armature slot, and in which the coil sides therein that are nearer the bottom of the slot are of coils having a smaller number of conductors.

8. An armature construction as claimed in claim 5, in which the said coil sides in the armature slot are positioned at different radial distances from the axis of the said armature core and in which differences in the numbers of conductors in the coils of said groups from the mean or average value thereof are relatively small and in conjunction with the said different radial distances of the said coil slots, give said coils of different numbers of conductors inductive reactances at least approximating equality.

9. In apparatus of the character described, in combination, a slotted armature, a commutator having a plurality of segments, an armature winding comprising two groups of coils, the one group consisting of coils with a smaller number of conductors than those of the other group, the said coils being arranged in such a way, that in each slot two coil sides with a smaller number of conductors lie on the bottom of the slot and two coil sides with a larger number of conductors lie above these coil sides and the departures, from the mean or average value, in the said numbers of conductors in the coils of said two groups being relatively small and proportioned, with respect to the differences in the magnetic circuits of said coils of said two groups, so that the inductive reactances of said coils at least approximate equality, and connections from said coils to the said commutator.

HUGO GROB.
